WILLIAM GIERTH AND GEORGE LATIMER, JR., OF NEWARK, NEW JERSEY.

ELECTRIC SIGN.

No. 823,774.

Specification of Letters Patent.

Patented June 19, 1906.

Application filed October 20, 1905. Serial No. 283,564.

To all whom it may concern:

Be it known that we, WILLIAM GIERTH and GEORGE LATIMER, JR., of Newark, in the county of Essex and State of New Jersey, 5 have invented a new and Improved Electric Sign, of which the following is a full, clear, and exact description.

This invention is designed to provide a sign that is made up of boxes containing electrical connections, each box in itself having on its face a letter, numeral, or design, the series of boxes going to make up a sign.

A further object of the invention is to provide a box of this kind that can be used on 15 both sides for a sign, or one of the sides can be made plain to form a back.

Another feature of the invention is a connection between the boxes that is quickly disconnected, this disconnection allowing the 20 withdrawal of any of the boxes from the sign for repairs or substitution without taking down the whole structure. The faces of the boxes and their connection with the current-supply can be quickly removed without disturbing the whole boxing and can be as 25 quickly replaced.

The invention is illustrated in the accompanying drawings, in which—

Figure 1 shows a sign attached to a building with one of the faces of the boxes removed, but showing one-half of one of the faces in place. Fig. 2 is a vertical section of one of the boxes with one of the faces and its connection disconnected from the box. Fig. 3 35 is a vertical section of the detail, showing the telescopic connection between the boxes; and Fig. 4 is a face view of one of the tubes used in this telescopic connection shown in Fig. 3.

In the drawings, 10 is any suitable frame 40 designed to hold, by means of the braces or brackets 11, the boxes 12. The top of the boxes 12 have overhangs 12^a, so that when the face-plates 13 are in place they form a lap to keep out moisture, and the face-plates 45 13 are also provided with similar laps on the side to fit over the edges of the boxes 12. The lamp-sockets 14, that are designed to carry the lamps 15, are disposed on the face-plates to form the required characters, and 50 the face-plates are securely fastened to the boxes 12 by means of bolts 16 on the lugs 17, which receive a thumb-screw 18. This is a preferred form of fastening, although it is evident that any suitable means can be substituted therefor.

Inside of each box is a tube 19, that can

be split in any way on the end, but preferably as shown in Fig. 4, where the cuts 19^a give the end of the tube a certain resiliency. The lower half of this split portion is sweated or secured in any way to a boss 20, and a set-screw 21 can be screwed down to decrease the diameter of the tube. These ends of the tubes in this way can be made to tightly grasp the rod 22, thereby forming an electrical connection between the rods and the tubes. The adjacent faces of the boxes on the sides are provided with the bushings 23, which have a lining of insulation 24 and are tightly secured in place by the nuts 25. Suitable lead washers 26 can be inserted to make the joint waterproof. These insulated bushings form the channel through which the rods 22 pass from one box to another, and they carry the current that is brought into the box by means of the wires 31. (Shown in Fig. 1.) It will be seen that any number of boxes can be put side by side and connected in this way and that when a box is found that needs removal or substitution by simply loosening the screws 21 on either end of the two rods 22, that pass from one object to another, the rods can be slipped back into one or the other of the tubes, and the box that requires removal can be lifted off when the brackets 11 are loosened. In the same way when a sign is enlarged new boxes are simply added on, and the caps 23^a, which are arranged on the ends of the last box on either end, are removed, bushings 23 substituted, 90 and the rod 22 on that end instead of abutting into a cap run into the next succeeding tube.

Washers 22^a, of insulating material, are arranged on the rods 22 to protect the nuts 25 from any possible contact with the rod 22. Suitably disposed on the tubes 19 are the binders 27, which are made in halves and fit over the tubes, being drawn together by the screw 28. Between the head of the screw 28 and the binder 27 can be arranged the terminal 29 of the wire 30^a, which supplies one of the wires of the lamp-sockets, and if the opposite face of the box is used for sign purposes another terminal 29 can be placed on the other end of the screw and a nut 30 used to bind them all tightly together. If the back of the sign is desired to be left plain, the nut 30 is screwed up on the screw 28, and a plain cover can be put on the back of the box. This arrangement for attaching the terminals of the system of wiring on one of

the faces of the box allows the removal of any face at any time without interfering with the lighting of any of the other boxes.

Having thus fully described our invention, we claim as new and desire to secure by Letters Patent—

1. An electric sign comprising a series of boxes having characters formed of electric lights on their faces, rigid conductors in the boxes for transmission of the electric current, electrical connections between the rigid conductors and the lights on the faces of the boxes, and telescopic connection between the rigid conductors in one box to the rigid conductors in the next succeeding box.
2. An electric sign comprising a series of boxes, faces carrying characters made of electric lights, rigid conductors in the boxes for transmission of an electric current, electrical connection from the rigid conductors to the lights on the faces of the boxes, insulated hollow connections between the boxes, and telescopic connection between the rigid conductors in each box to the rigid conductor in the next succeeding box, telescopic connection passing through the insulated connection between the boxes.
3. An electric sign comprising a series of

boxes, rigid conductors in each box having hollow ends, insulated couplings connecting the boxes, and rods arranged to fit in the hollow ends of the rigid conductors and passing through the insulated connection, said rods sliding in the hollow ends of the conductors, and clamps on the ends of the rigid conductors to fasten the rods in the conductors.

4. An electric sign comprising a series of boxes, rigid conductors in each box telescopically connected to the rigid conductors in the next succeeding box, face-plates on the boxes carrying lamp-sockets, and means for connecting each rigid conductor with the sockets on each face of each box.

5. A box for an electric sign comprising a casing, a removable face on each side of the casing, lamp-sockets arranged on each face, a pair of rigid conductors in the box, means for connecting the pair of conductors with an electric circuit, and binders connecting the circuit of each face of the box with the rigid conductors.
